UNITED STATES PATENT OFFICE.

MARSHALL W. GROOM, OF SAN JOSE, CALIFORNIA.

CAN EXHAUSTER AND COOKER.

No. 808,044.

Specification of Letters Patent.

Patented Dec. 19, 1905.

Application filed March 24, 1905. Serial No. 251,915.

To all whom it may concern:

Be it known that I, MARSHALL W. GROOM, a citizen of the United States, residing at San Jose, in the county of Santa Clara and State 5 of California, have invented new and useful Improvements in Can Exhausters and Cookers, of which the following is a specification.

My invention relates to apparatus for use in canneries, and especially in fruit and vegetable canneries.

In fruit-canneries it is usual, first, to charge the cans with the fruit; second, to fill them with syrup; third, pass the syruped cans through an exhaust-box, where the cans are 15 heated up to drive out the air; fourth, cap the cans; fifth, cook the cans by passing through an apparatus similar to the exhaust-box, but where the heating period is prolonged, cooling and traying the cans, and, 20 finally, preparing them ready for the market.

My invention pertains to the exhausting and cooking periods; and its object is to provide an apparatus which will be simple, practical, and economical and of large capacity, 25 which may be used for either exhaust or cooking purposes, which will enable cans to be exhausted or cooked for any length of time within certain limits without changing the speed of travel of the cans and without losing time 30 in making the change, and, conversely, which will permit the speed of the cans to be changed without changing the time of exhausting or cooking and which will prevent the open cans filling with the drip from the condensed steam 35 during exhaust and so diluting the syrup or causing the cans to overflow and foul the outside of the cans and the apparatus with syrup to the serious inconvenience of the solderer.

The invention consists of the parts and the 40 combination of parts hereinafter described, having reference to the accompanying drawings, in which—

Figure 1 is a plan view of my apparatus with top removed, showing runways, but 45 omitting the heating-pipes. Fig. 2 is a side elevation of same. Fig. 3 is an end elevation of same. Fig. 4 is a transverse section on the line $z-z$ of Fig. 5, showing steam-pipes. Fig. 5 is plan view of heating-pipes. Fig. 6 50 is a side view of tightener for the can-carriers. Fig. 7 is a section on the line $y-y$ of Fig. 6 through same.

A represents a suitable framework supporting the box 2, which is of suitable size, 55 shape, and material. This box is inclosed

top and bottom and on all sides except for an ingress-opening 3 at one side adjacent to one end for the cans and a similar egress-opening 4 in the opposite side approximate to the opposite end. The box is divided longitudinally into a plurality of compartments or runs 5 by means of the partitions 6.

A can entering at 3 is taken by suitable conveying means along the first run to the opposite end of the machine, where by means 60 of a curved guide 7 and a revolving shaft 8 the can is shunted over into the next run, where an oppositely-traveling carrier conveys the can to the other end of the machine, and so on, alternating back and forth across 65 the machine until it is discharged at 4. Similar guides 7 are disposed at each end of the machine to effect the necessary deflection from one run to another, and a similar shifting device 8, revolving in the right direction, 70 is arranged properly between the succeeding pairs of runs.

Any suitable conveying means may be employed to carry the cans through the runs. Preferably I use a separate conveyer for each 80 run, which comprises a chain 9 passing over end sprockets 10 turning on horizontal axes, and which chain carries the slats 11 whereon the cans set. The ends of the slats are guided and supported in their upper and 85 lower flights on the angles 12, attached to the sides of the partitions 6, as shown in Fig. 4. The conveyers are entirely housed in the box and being supported along their lower planes require very much less power to run them 90 than where they hang limp and unsupported underneath and outside the box, as is usual with exhausters of this character.

As shown in Fig. 1, there are two sets of shafts for the sprockets 10, one set 13 13^a and 95 the other, 14 14^a, all disposed horizontal and parallel and substantially in the same plane, but with the shaft 13 outside of shaft 14 and shaft 13^a inside of shaft 14^a, so that alternate conveyers begin and terminate at different 100 points from the intermediate conveyers for the purpose of allowing the cans to be properly shifted from one conveyer to a next succeeding one. Furthermore, the two sets of shafts are revolved in opposite directions by 105 the interengaging gears 15. The partitions 6 likewise terminate at different points, so that the cans may pass around a partition at each end of the machine into a succeeding run throughout the series.

- The transverse roller-conveyers 8 are journaled between, parallel with, and approximately in the plane of the several longitudinal conveyers 9 and are operated conjunctively with the latter to transfer the cans from one run to the other. The several rollers 8 at either end of the apparatus are driven in unison from the shaft 16 through corresponding beveled gearing 17.
- 10 Power to operate the several conveyers may be derived from any appropriate source, and any suitable form of drive connections may be employed to operate the conveyers in unison. It is desired, however, that means 15 be provided by which the conveyers may be run at different speeds to diminish or increase the capacity of the machine or to vary the period of exhausting or cooking or to save power.
- 20 18 represents a drive-shaft which may be run at constant speed. This shaft has three normally idle sprockets 19 20 21, any one of which is adapted to be run in unison with the shaft by means of suitable respective clutches 25 22, sliding on and turning with the shaft.
- 23 is a counter-shaft carrying three sprockets 24 25 26, each of different size, connected with the respective sprockets 19 20 21 by corresponding chains 27. From shaft 23 a 30 chain 28 passes over sprockets 29 29', the shaft of which latter sprocket carries a small gear 29^a, engaging the large gear 30 on the shaft 14^a.
- 35 Shaft 14^a is connected with the adjacent shaft 16 by the sprocket-chain 31, while the shaft 13 at the opposite end of the machine is connected with the other shaft 16 by chain 32. The shafts 13 14 may have their journal-boxes mounted on sliding carriages 33, 40 movable by the screws 34 to permit the simultaneous adjustment of the tension of all the carriers 9, and the tension of chain 32 may be regulated by a suitable tightener 35. Since there may be three carriages 33 to support the shafts 13 14, as here shown, and as 45 they must be moved in unison, each screw 34 extends outside the box and carries a sprocket 36, while a chain 37 passes over all these sprockets and around a tightener 38. By operating a crank 39 on one of the screws all are 50 turned simultaneously, equally, and in the same direction to move the carriage as desired.
- 55 The heating of each of the several runs is done independently of one another, so that a can may traverse one run at cooking or exhausting temperature and on passing into the next run will traverse a cooler and non-cooking or non-exhausting zone. As here shown, 60 a perforated steam-pipe 40 extends from end to end of each run between the upper and lower flights of the conveyers 9 and is connected laterally through the middle of the machine by a corresponding pipe 41 with the 65 main steam-pipe 42. Valves 43 regulate the

passage of steam through pipes 41 to the respective runs.

The roof of each run of the box is preferably made arched, as shown, so that the moisture condensing in the top of the runs will run off down the sides of the partitions 6 and not drip into the open cans when the device is used as an exhauster. This drip in ordinary flat-topped boxes is most annoying and uneconomical, since it causes a dilution of the 70 syrup and overflowing of the can and a consequent waste of syrup and sugar, besides causing a sloppy mess in the exhauster and on the conveyers and interfering seriously with the soldering of the cans, since they must be 80 cleaned of all sugar deposits around the cap-opening before the solder will take hold.

Access may be had to either end of the runs and to the various conveyer-shafts through the hinged doors 44. A thermometer 45 is 85 disposed relative to each run, so the temperature of the several runs may be accurately gaged.

The points to be emphasized especially in this machine are the inclosed box with the 90 separated runs opening one into the other at the ends and the conveyers 9 in the runs and supported in the box; the horizontal rollers 8, by which the cans are shifted around the turns and which revolve as fast as the surface travel of the longitudinal conveyers carrying the cans, and which rollers prevent the cans stopping at the turns, thereby avoiding any blocking or clogging in the apparatus; the three-speed arrangement for varying the 95 rate of travel of the cans; the separately-regulated steam-pipes to permit cooking or exhausting to continue a longer or shorter time without varying the rate of travel of the cans.

An exhauster or cooker of six thousand 100 cans capacity per hour would be approximately thirty-two feet long, with six runs in the exhauster or twelve in the cooker. Giving one minute for a can to traverse a run, it would take six minutes for exhausting and 110 twelve for cooking, which are the usual times for most fruits. With this apparatus there may be two or more different times of cooking or exhaust going on simultaneously. If the operator desires to shorten the cook without changing the speed of travel of the cans, he turns off the proper number of throttles 43 to bring down the time to the point desired. Then when he wishes to add more time he turns on the steam in the proper 120 number of runs. Hence he is able to cook each lot of fruit just the requisite amount without loss of time by having to empty the cooker first and then speed it up before feeding in a fresh lot, as must be done with the apparatuses now commonly in use. By this apparatus he can keep running and can accomplish the desired end by turning off or on one or more steam-valves. If with a machine 125 of six thousand cans normal capacity per 130

hour the cans should only come at the rate of four thousand five hundred per hour and the operator wants to give them the same cook as before—say twelve minutes—he 5 throws out the high-speed clutch and runs at intermediate speed and cuts off steam in two runs in the exhaust-box and in four runs in the cooker, which will just handle four thousand five hundred cans, and thus save power and labor. When the cans begin to come faster, he speeds up his machine and turns on steam in the proper number of runs or compartments in the exhauster and cooker (it being understood that the exhauster is separate from the cooker, but both identical in principle. Thus it is observed that with this machine I may vary the length of the period of exhaust or cooking (the heating period) without changing the speed of travel 10 of the cans, or, conversely, I may vary the speed of travel of the cans without changing the lengths of the heating period.

It is possible that various modifications may be made in this invention without departing from the principle thereof, and I do not wish to be understood as limiting myself to the specific construction herein shown and described.

The cans may be fed into the device 15 through a suitable inlet-opening by any well-known means and onto a conveyer 70, (shown by dotted lines in Figs. 1 and 2,) by which they are carried into the first runway.

Having thus described my invention, what 20 I claim, and desire to secure by Letters Patent, is—

1. In an apparatus of the class described, the combination of a retort having ingress and egress openings for the cans and divided 25 longitudinally into a plurality of runs having communication with each other at their ends, separate conveyers operating in said runs, and entirely housed and supported in the retort, means for operating alternate of said conveyers in one direction and means for operating the intermediate conveyers in an opposite direction, rollers at the ends of the runs between the conveyers and guides coöperating with said rollers to transfer the cans 30 from one of said conveyers to a succeeding oppositely-moving one, and heating means within the retort.

2. In an apparatus of the class described, the combination of a retort having ingress 35 and egress openings for the cans and divided longitudinally into a plurality of runs having communication with each other at their ends, separate conveyers operating in said runs, and entirely housed and supported in the retort, means for operating alternate of said conveyers in one direction and means for operating the intermediate conveyers in an opposite direction, rollers at the ends of the runs between the conveyers and guides coöperating with said rollers to transfer the cans 40

from one of said conveyers to a succeeding oppositely-moving one, and separately-controlled heating means in each run.

3. In an apparatus of the class described, the combination of a retort having ingress 45 and egress openings for the cans and divided longitudinally into a plurality of runs having communication with each other at their ends, separate conveyers operating in said runs and entirely housed and supported in the retort, means for operating alternate of said conveyers in one direction and means for operating the intermediate conveyers in an opposite direction, rollers at the ends of the runs between the conveyers and guides coöperating with said rollers to transfer the cans 50 from one of said conveyers to a succeeding oppositely-moving one, and separately-controlled heating means in each run, the runs in said retort having arched roofs whereby 55 the condensed moisture is directed to the sides of the runs.

4. In an apparatus of the class described, the combination of a retort having ingress and egress openings for the cans and divided 60 into a plurality of longitudinal runs, conveyers in said runs, means for operating alternate of the conveyers in one direction, and means for operating the intermediate conveyers in an opposite direction, means for transferring the cans at the ends of the runs from 65 one run to another progressively through the apparatus, means for heating the cans in the retort, and means for varying the heating period without changing the speed of said conveyers.

5. In an apparatus of the class described, the combination of a retort having ingress and egress openings for the cans and divided 70 into a plurality of longitudinal runs, conveyers in said runs, means for operating alternate of the conveyers in one direction, and means for operating the intermediate conveyers in an opposite direction, means for transferring the cans at the ends of the runs from 75 one run to another progressively through the apparatus, means for heating the cans in the retort, and means for varying the heating period without changing the speed of said conveyers, and means for varying the speed of the 80 conveyers without altering the heating period for the cans.

6. In an apparatus of the class described, the combination of a box divided longitudinally into a plurality of runs, conveyers in 85 said runs, means for operating alternate of the conveyers in one direction, and means for operating the intermediate conveyers in the opposite direction, means for transferring cans from one conveyer to another, heating means in the apparatus, and means for varying the speed of said conveyers without changing the heating period of the cans in the apparatus.

7. In an apparatus of the class described, 90

- the combination of a closed box divided longitudinally into a plurality of compartments connected at the rims, conveyers operating in said compartments, said conveyers comprising chains passing over sprockets on horizontal axes, slats on the chains and guides on the sides of the compartments supporting said slats, means for operating alternate conveyers in one direction, means for operating the intermediate conveyers in the opposite direction, transfer means between the conveyers to shift the cans from one conveyer to a succeeding one, heating means in the compartments, and means for controlling the heat in each compartment independently of all the other compartments.
8. The combination of a box divided longitudinally into a plurality of compartments, heating means in the compartments, endless conveyers on horizontal axes traveling in said compartments, means for operating the conveyers in alternate compartments in one direction, means for operating the intermediate conveyers in an opposite direction, horizontally - disposed rollers arranged parallel with and between the conveyers and curved

guides coöperating with said rollers to shift the cans from one conveyer to another at the turns, and means for operating said rollers.

9. The combination of a box divided longitudinally into a plurality of compartments, conveyers on horizontal axes in said compartments, one set of shafts supporting alternate of said conveyers and another set of shafts supporting the intermediate conveyers, connections between said sets of shafts, said shafts at one end of the apparatus being mounted in boxes to move in unison, means for shifting said boxes to vary simultaneously the tension of all of said conveyers, heating means in the compartments and transfer means operating between successive conveyers to shift cans from one conveyer to a succeeding conveyer.

In testimony whereof I have hereunto set my hand in presence of two subscribing witnesses.

MARSHALL W. GROOM.
